Des. 795

Thomas A. Herrick, of East Bridgewater, Mass
Ass't to, Lemuel M. Leonard of Taunton, Mass:
Letters Patent N°. 795, Dated May 20th, 1856.

The schedule referred to in these Letters Patent, and making part
of the same.

To all persons to whom these Presents shall come:

Be it known that I, Thomas A. Herrick of East
Bridgewater, in the County of Plymouth, and State of Massa-
chusetts, have invented or produced a new ornamental Design
for the sides and doors of a cooking stove; And I do hereby declare
that the same is fully represented in the accompanying drawings,
of which,

Figure 1, is a front view or elevation of the side plate,
of a stove and its doors as formed and ornamented in accordance
with my design.

Figure 2, is a vertical section of the above taken
through the middle of the larger door.

Figure 3, a horizontal section of the side plate.

Figure 4, a vertical section, of the side plate and
smaller door, the same being taken through the middle of the
latter.

The side plate A, has a circumscribing moulding
a, applied to it as seen in Figures 1 and 2. It has also a raised
panel B, formed with a circumscribing band b, around which
is a chain of elongated four pointed stars, the same enclosing
or surrounding a fluted rectangular projection c. — Each of
the doors D, E, is formed with a rosette of rays in relief, as seen
at fig. 9, the same springing from a sunken panel, which is
bordered by a line of four pointed stars, and contains in each
of its opposite angles an ornament in bas relief, composed of

2

Dec. 795.

three elongated four pointed stars radiating from a common center. The square panel P, of the side plate is formed so far as its ornamental character is concerned, like the smaller doors.

The character of the various moldings, as well as the extent of relief, of the various ornaments, will readily be discerned from the drawings, and any patternmaker of ordinary skill will find no difficulty in comprehending from said drawings, and producing by means of them, the ornamental design which is the subject of my invention.

I claim the ornamental design of each of the doors and side plate as represented in the drawings, and as above described.

In testimony whereof, I have hereunto set my signature, this twenty fourth day of March A.D. 1856.

Witness
